UNITED STATES PATENT OFFICE.

JOSEPH McMILLAN, OF GLENDALE, AND CLARENCE V. GREENAMYER, OF LOS ANGELES, CALIFORNIA.

CURRENT-COLLECTOR FOR ELECTRIC CARS.

1,221,762.

Specification of Letters Patent.

Patented Apr. 3, 1917.

Application filed July 15, 1915. Serial No. 39,956.

To all whom it may concern:

Be it known that we, JOSEPH McMILLAN and CLARENCE V. GREENAMYER, citizens of the United States, said McMILLAN residing at Glendale and said GREENAMYER residing at Los Angeles, county of Los Angeles, and State of California, have invented new and useful Improvements in Current-Collectors for Electric Cars, of which the following is 10 a specification.

This invention relates primarily to a current collector for use on electric railways and the object thereof is to provide a current collector that will be equally efficient 15 with cars running at high speed or low speed.

It has been found that when electric cars are run at a speed over thirty miles per hour that part of the collector which takes the 20 current from the feed wire has at all times a tendency to leave the wire and does leave the wire frequently for short distances thereby breaking the circuit and causing frequent arcs which produce a destructive effect upon 25 the insulation of all electrified parts and produces a rapid deterioration of the conductor and feed wire. The object of our invention is to produce a collector in which the traveling portion will not at any time or 30 under any running conditions accidentally leave the feed wire and will at all times when the car is running engage the feed wire with a pressure sufficient to produce a reliable working contact.

35 In the drawings forming a part of this application:

Figure 1 is a side elevation of a portion of a car with our improved collector.

Fig. 2 is an end elevation of our collector 40 and a portion of a car.

Fig. 3 is an enlarged central longitudinal section, partly broken away, of a portion of the base of the collector.

Fig. 4 is a top plan of the parts shown in 45 Fig. 3.

Fig. 5 is a detail of the contact collector with parts in elevation, parts in section, and parts broken away.

Fig. 6 is a central vertical section of the 50 controller valve.

Figs. 7, 7^a, 7^b, and 7^c show a modified form of the contact member.

In the drawings 9 is an electric car upon the roof of which the main parts of our col-

lector are carried. To the roof of the car is 55 bolted a base block 10 having an L-shaped channel 11 therein. From this channel runs a pipe 12 to controller valve 13 at one end of the car. A branch pipe 14 runs from pipe 12 to a like controller valve (not shown) at 60 the other end of the car. These controller valves are located so as to be readily accessible to the motorman and are connected separately to a compressed air reservoir 8 carried beneath the car.

65 The controller valve consists of a body casing 15 forming a valve chamber 16 in the lower portion of which is a port 17 to which pipe 12 is connected. Opposite port 17 is port 18. In the casing is a rotary valve plug 70 19 which has a main or feed channel 20 running or extending transversely therethrough, which channel, when the car is running, connects ports 17 and 18. A branch channel 21 runs from channel 20 to the edge of the plug 75 and may be termed the release channel. Plug 19 has an operating handle 22 by means of which the plug is operated. An index with points marked thereon is placed near the handle. When the handle is 80 brought to register with point 23 the plug is in the running position and ports 17 and 18 are fully opened and connected and the air passes into a piston chamber as hereafter explained. When the handle is brought to 85 point 24 ports 17 and 18 are only slightly opened. When the handle is brought to point 25 ports 17 and 18 are blanked. Casing 15 has another port 26 which is intermediate ports 17 and 18 and is connected to 90 channel 27 in release valve casing 28. In casing 28 is a chamber 29 which has a T-shaped outlet port 30. The inner end of port 30 is normally closed by a valve plug 31 which has a stem 32 projecting through the 95 casing and terminating in a button 33. A spring 34 normally holds plug 31 on its seat to close port 30. A bleed hole 35 opens into channel 27 and is regulated by a screw 36. When handle 22 is brought to point 37 channel 21 is brought into register with port 18 and channel 20 is brought into register with port 26 and the air from the piston chamber may slowly pass out of bleed hole 35. If a quick release is desired valve 31 is unseated 100 and the air quickly escapes through port 30.

105 An air cylinder 38 is connected to base block 10 by a ball and socket joint having a chan-

nel 39 therethrough which connects chamber 40 in the cylinder with channel 11. A piston 41 has a working fit in cylinder 40. A piston stem 42 is connected to piston 41 and extends through the end of cylinder 38 and is connected to cross bar 43 which cross bar is rotatively connected to and carried by elevating rods 44 and 45 the lower ends of which are hingedly connected to bearing blocks 46 and 47 secured upon the top of the car. Blocks 46 and 47 are connected by rods 48 and 49 to base block 10. Mounted on stem 42 between casing 38 and cross bar 43 is a plurality of springs of different strengths 15 for a purpose hereafter explained. Rods 44 and 45 are preferably cross braced by diagonal brace rods 51. Pivotally connected to cross bar 43 are carrying rods 52 and 53 in the outer ends of which is revolvably mounted rod 54. On rod 54 is revolvably mounted the contact roller 55 which, when the car is running, engages the feed wire 56. Roller 55 is a hollow cylinder of conducting material and at the ends thereof carries members 25 of ball races, one of which is shown at 57, which coact with members of races on rod 54, one of which is shown at 58, and with balls 59 and rollers 60 form a ball bearing between rod 54 and roller 55. The member 30 of ball races carried by roller 55 carry contact springs 61 which engage rod 54 and conduct the current from the roller to the rod. Bar 43 and rods 44, 45 and rods 52 and 53 form a main toggle or hinge. A current pole 62 is forked at its upper end and revolvably secured to rod 54. The lower end of pole 62 is pivotally connected to base block 10. Suitable wiring connects the lower end of the pole to the motors (not shown) on the 35 car. On the outer ends of rod 54 are secured shields or projections 63 which slope downwardly at their outer ends. These shields are used to prevent the roller from slipping from beneath the feed wire in case of an unusual sway of the car. A ball bearing joint 40 is preferably provided between the end of the air cylinder 38 and the piston stem 42.

In the operation of our current collector it will be observed that before air is turned 50 into chamber 40 the weight of the parts will cause roller 55 and connected parts to assume a position close to the top of the car. In this position the springs 50 on the piston stem 42 will be compressed and hold the air cylinder 38 and rods 44 and 45 at their connected points slightly above the tie rods 48 and 49 and when air is admitted into chamber 40 these springs will assist the air at the start in raising the roller 55 to engage 55 the feed wire. After the roller has been elevated a few feet the spring action ceases and thereafter the roller is raised by the air pressure on piston 41 in chamber 40. The ordinary height of the feed wire 60 is eight feet and the parts will be so con-

structed and arranged that the carrying rods 52 and 53 are vertical at such height, and when these rods are in alinement with rods 44 and 45 the contact roller will be carried upward to the extreme height of the feed wire. At this time the piston is at its extreme outward position and rods 44 and 45 are prevented from further movement away from the piston chamber. As before stated when there is no air in the piston chamber the parts lie close to the top of the car and the springs on the piston stem hold the contact roller at a short distance above the roof of the car. In order to make the initial raise of the contact roller with the usual air contact pressure easier we provide an auxiliary piston 64 which has a working fit in cylinder 65 which cylinder is connected by pipe 66 with pipe 12. Piston 64 has a stem 67 upon which cross bar 43 rests when there is no air in cylinder 38.

When the air is turned into pipe 12 it flows into cylinders 38 and 65 and the contact roller is started upwardly by the combined air pressure on the pistons in both cylinders aided by the resiliency of the springs 50 on stem 42. If desired this auxiliary air cylinder and connected parts may be omitted but we prefer its use as a quicker raise of the contact roller from its position of non-use is effected by its use.

In Figs. 7, 7^a, 7^b, and 7^c we have shown a modified form of the contact member. In this form we use a rod 64 preferably square instead of round rod 54, and instead of cylinder 55 we use a wheel. This wheel is constructed as follows. Slidably mounted on rod 64 is the inner member 65 of a ball and roller race. In the ends of member 65 are raceways 66 in which are mounted rollers 67 which bear against the sides of rod 64. These rollers are held positioned by cap plates 68 which are held in place by screws 69. The outer surface of member 65 is circular and forms one side of a raceway 70 in which are mounted balls and rollers as shown in Fig. 5, balls 71 being shown in Fig. 7^a. The hub 72 carries the outer member 73 of race way 70. For lightness of construction we provide a deep groove 74 in the outer edges of the hub. Secured to the hub at each of the sides thereof and insulated therefrom by insulation 75 are plates 76 and 77. These plates carry a grooved circular rim 78 which, when in operative position, engages the feed wire. Plate 76 carries a circular flange 76^a made integral therewith which is engaged by contact springs 79 which are secured to plate 68. There may be as many of these contact springs as are desirable. Mounted upon rod 64 is a U-shaped guard 80 which will engage the feed wire and hold the wheel from damaging the span wires in case the wheel should come off the feed wire. A washer 81

is secured to hub 72 to assist in holding the hub in alinement with member 65. In this construction the wheel can slide along rod 64 to adjust itself to the sway of the car 5 when running. When the rim is worn out a new rim may be substituted and the wheel is as good as a new wheel. In all other respects the parts of our collector are as first described.

10 By this construction it will be observed that we have provided a current collector composed of parts that form triangles when in a working position and act on the truss principle and enables the car to be run in 15 either direction without turning the collector. It will also be observed that the contact member is carried principally by hinged members which form a toggle and that the contact pole acts as a brace, and that the 20 power is applied to the center of the main supporting hinge to maintain the contact member in engagement with the feed wire.

This construction enables the power to be applied so as to produce high efficiency 25 with small power. By the triangular construction the usual shocking of the contact member when running at high speeds is almost entirely eliminated and arcing is almost entirely avoided.

30 Having described our invention what we claim is:

1. In combination a car; a current collector mounted thereon, said collector comprising a contact member adapted to engage an 35 overhead feed wire; hinged members car-

rying said contact member, one of the ends of said hinged members being pivotally connected to the car and the other ends carrying said contact member; a bracing guide pivotally connected to the car and to the 40 contact member; and pneumatically operated means applied at the joint between said hinged members adapted to force the contact member against an overhead feed wire.

2. In combination a car; a toggle mounted thereon; a contact member adapted to engage an overhead feed wire carried by said toggle; a brace pivotally mounted on the car and connected to said contact member; an air cylinder mounted on the car; a 50 piston in said cylinder operatively connected to said toggle at its central joint whereby when air is admitted into said cylinder said toggle causes said contact member to press on an overhead feed wire. 55

3. In a current collector for electric cars having an overhead feed wire, a contact member; supporting and bracing means for said member, said supporting means being hingedly jointed near the center thereof and pneumatically operated means connected to 60 said supporting means at the joint therein adapted to exert a pressure upwardly on said contact member from a point directly below said contact member under ordinary 65 running conditions.

In witness that we claim the foregoing we have hereunto subscribed our names.

JOSEPH McMILLAN.

CLARENCE V. GREENAMYER.
